UNITED STATES PATENT OFFICE.

JOHN A. BRILL, OF PHILADELPHIA, PENNSYLVANIA.

DESIGN FOR AN UPPER CHORD FOR CAR-TRUCKS.

SPECIFICATION forming part of Design No. 22,492, dated May 30, 1893.

Application filed February 4, 1893. Serial No. 461,074. Term of patent 14 years.

To all whom it may concern:

Be it known that I, JOHN A. BRILL, a citizen of the United States, residing at Philadelphia, in the county of Philadelphia and State 5 of Pennsylvania, have invented a new and useful Design for Upper Chords for Trucks, of which the following is a specification, reference being had to the accompanying drawing, forming a part thereof.

- o A leading feature of my design consists in the peculiar conformation of the upper chord of the truck.

In the drawing forming a part of this specification the figure is a plan view of the upper 5 chord.

In the figure is shown the upper chord, which comprises the cross bar 1, the side bars 2 extending at right angles from the cross bar

and continuous therewith, oblique sections 3 of the side bars and a cross bar 4 uniting the 20 oblique sections, the union of all the parts being made curved instead of angular, as shown at 5, the whole forming a figure having a rectangular base and a trunco pyramidal top, or apex. Circular apertures 6 are 25 formed in the chord.

Having described my invention, I claim—

The design for the upper chord of a truck, substantially as herein set forth.

Signed at the city of Philadelphia, county 30 of Philadelphia, and State of Pennsylvania, this 1st day of February, 1893.

JOHN A. BRILL.
